LOCOMOTIVE STOKER

Washington T. Capps, Baltimore, Md., assignor,
by mesne assignments, to The Standard Stoker
Company, Inc., New York, N. Y., a corporation
of Delaware

Application April 10, 1935, Serial No. 15,515

4 Claims. (Cl. 198—15)

My invention relates generally to stokers for application to a locomotive and tender and more specifically to stokers of the type comprising a plurality of fuel conveyors arranged with two 5 of the conveyors offset laterally from each other at their adjacent ends and having independent drive connections at their rearward ends.

The principal object of the invention resides in the provision of a stoker of the type described 10 in which the angular relation between the conveyors is substantially reduced and in which the fuel will be conveyed from the tender to the locomotive in the most direct course consistent with available space between the deck and frame 15 of the locomotive and tender.

More specifically, the invention contemplates the provision of a stoker having a fuel receiving conveyor on the tender, a fuel delivery conveyor on the locomotive, and an intermediate conveyor, the latter being offset laterally at one end from an adjacent end of one of the other conveyors and said adjacent end of that conveyor disposed at one side of the vertical medial plane of the locomotive and tender or at one 25 side of the vertical medial plane of the other of said conveyors, and wherein the intermediate conveyor and trough conveyor are in approximate horizontal alignment, and the delivery conveyor, trough conveyor and intermediate conveyor each has its axis substantially parallel to the vertical medial plane of the locomotive and tender.

Another object of the invention resides in the provision of a specific embodiment as above 35 wherein the rearward end of the intermediate conveyor is offset laterally from the forward end of the tender conveyor.

Another object of the invention resides in the provision of a specific embodiment as above 40 wherein the tender conveyor is disposed with the axis thereof at one side of and substantially parallel to the vertical medial plane of the tender.

To the above and other ends the invention 45 consists in the arrangement of parts and in their relation and association one with the other or in combination as hereinafter described and as illustrated in the accompanying drawing, in which,

Fig. 1 is a longitudinal, vertical, central section of adjacent portions of a locomotive and tender with the novel stoker applied thereto and shown in elevation with parts broken away; and

Fig. 2 is a plan view of the stoker structure shown in Fig. 1.

On the drawing, the locomotive and tender are represented generally by the letters A and B, respectively, and the coupling member therebetween, permitting articulation when the locomotive and tender are rounding curves or passing over switches and turntables. Mounted within the intermediate conduit 26 is a conveyor screw 31, the forward end of which is connected to the elevating screw 20 by a universal joint 32. The intermediate conduit 26 and the intermediate conveyor screw 31 are so disposed that the inter-

the letter C. The locomotive A comprises a frame 10, a boiler 11 provided with a hollow backwall 12 having a firing opening 13, and a firebox 14. The tender B includes a frame 15, a fuel bin 16 having a floor 17 which is provided with a central longitudinally extending opening 18.

Fuel is conveyed from the tender fuel bin to the firebox 14 by stoker mechanism indicated generally at S. The stoker mechanism S includes the fuel receiving or tender conveyor D mounted on the tender frame 15 beneath the fuel bin 16 to receive fuel through the opening 18, a delivery conveyor E mounted on the locomotive and an intermediate conveyor F.

The delivery conveyor E includes an inclined conduit 19 communicating with the firebox 14 through the firing opening 13, and an elevating or fuel delivery conveyor screw 20 housed within the conduit 19 for delivering fuel to a distributing means 21 which is arranged to spread the fuel to all parts of the firebed. The conduit 19 and its elevating screw 20 are mounted so that their respective axes lie substantially in the vertical medial plane of the locomotive and tender.

The fuel receiving or tender conveyor D includes the trough-like conduit 22 and a conveyor screw 23 mounted therein for advancing fuel therethrough. The trough-like conduit 22 and the conveyor screw 23 are so disposed on the tender that the axis of the conveyor screw 23 lies at one side of and is parallel to the vertical medial plane of the locomotive and tender. The tender conveyor D is also provided with a tubular portion 24 communicating with and extending forwardly from the open forward end of the trough-like conduit 22. A spherical member 25 is formed externally of the tubular portion 24 and at the forward end thereof.

Fuel passes from the tender conveyor D to the delivery conveyor E through the intermediate conveyor F. The conveyor F includes a conduit 26 which has a sleeve 27 slidably mounted on its forward end, the sleeve 27 being received in a spherical flange 28 formed with the lower end of the inclined conduit 19. The rearward portion of the intermediate conduit 26 is provided with a laterally and rearwardly extending elbow 29 having a spherical flange 30 formed with its rearward end arranged to receive the spherical member 25. The connections just described provide for the necessary articulation between the stoker conduit sections when the locomotive and tender are rounding curves or passing over switches and turntables. Mounted within the intermediate conduit 26 is a conveyor screw 31, the forward end of which is connected to the elevating screw 20 by a universal joint 32. The intermediate conduit 26 and the intermediate conveyor screw 31 are so disposed that the inter-

mediate conveyor screw 31 and the trough conveyor screw 23 are offset laterally in a horizontal direction with respect to each other and lie in approximately the same horizontal plane and the axis of the intermediate conveyor screw 31 lies substantially in the vertical medial plane of the locomotive and tender. The rearward end of the intermediate conduit 26 is provided with a cover 33 forming a bearing for the extended shaft 33a of the conveyor screw 31.

The drive means for the conveyor screws of the stoker includes the prime mover 34, a gear train 35 housed within the casing 36 at the rear of the trough 22, and suitable shafting which connects the prime mover 34 with the conveyor screws 23 and 31 for operating the same. The gear train 35 comprises the main gear 37 loosely mounted on the shaft 38 of the conveyor screw 23, a pinion gear 39 which meshes with the main gear 37 and is driven directly by the prime mover 34 through the shaft 40, and a gear 41 meshing with the main gear 37 and having operatively associated therewith a telescopic shaft 42 which is flexibly connected with the shaft 33a of the conveyor screw 31 for operating the same. On one side, the main gear 37 carries clutch teeth 43 which are normally engaged by clutch teeth 44 of the clutch member 45. The clutch member 45 is operatively mounted on the shaft 38 and slidably therealong by the shifting yoke 46 for selectively engaging or disengaging the clutch teeth 43 and 44.

In the normal operation of the device, the clutch member 45 is moved to a position causing the clutch teeth 44 to engage the clutch teeth 43, thereby operatively connecting the main gear 37 to the shaft 38. Operation of the prime mover 34 sets the entire gear train 35 in motion whereby the main gear 37 rotates the conveyor screw 23 and the gear 41 operates the conveyor screw 31 and its connected conveyor screw 20 by means of the driving shaft 42. Fuel drops through the opening 18 into the trough 22 and is urged forwardly by the screw 23 and thence laterally through the elbow 29 into the intermediate conduit 26. There the fuel is received by the screw 31, which, together with its universally connected screw 20, conveys and elevates the fuel to the distributing means 21 for delivery to the firebox.

At times extraneous material in the fuel will become lodged between the crusher 47 and the conveyor screw 23, rendering the entire conveying mechanism inoperative. The fireman may, by shifting the clutch 45, disengage the clutch teeth 44 from the clutch teeth 43, thereby disconnecting the shaft 38 and the conveyor screw 23 from its operative relation with the gear train 35. The gear train 35, however, remains in operative relation with the conveyor screws 31 and 20 and fuel may continue to be delivered to the firebox by raising the hinged cover 48 over the hopper 49 formed in the inclined conduit 26 and manually introducing fuel into the hopper 49.

I claim:

1. In a locomotive and tender, a stoker comprising a rearward conduit section on the tender, a forward conduit section on the locomotive and an intermediate conduit section, said intermediate conduit section being movably connected with said forward conduit section in end-to-end relation therewith and having its opposite end

offset laterally from and movably associated with said rearward conduit section, a screw section in each of said conduit sections, said screw sections being disposed in parallel vertical planes, the screw section in said rearward conduit section being mounted in an approximately horizontal plane and arranged with its axis offset laterally from the axis of said intermediate and forward conduit screw sections, the screw section in said intermediate conduit section lying in said aforesaid horizontal plane.

2. In a locomotive and tender, a stoker comprising a rearward conduit section on the tender, a forward conduit section on the locomotive and an intermediate conduit section, said intermediate conduit section being movably connected with said forward conduit section in end-to-end relation therewith and having its opposite end offset laterally from and movably associated with said rearward conduit section, a screw section in each of said conduit sections, said screw sections being disposed in parallel vertical planes, the screw section in said rearward conduit section being mounted in an approximately horizontal plane and offset laterally from the vertical medial plane of the locomotive and tender, the screw section in said intermediate conduit section lying in said aforesaid horizontal plane and being offset laterally from the screw section in said rearward conduit section.

3. In a locomotive and tender, a stoker comprising a rearward conduit section on the tender, a forward conduit section on the locomotive and an intermediate conduit section, said intermediate conduit section being movably connected with said forward conduit section in end-to-end relation therewith and having its opposite end offset laterally from and movably associated with said rearward conduit section, a screw section in each of said conduit sections, said screw sections being disposed in parallel vertical planes, the screw section in said rearward conduit section being mounted in an approximately horizontal plane and offset laterally from and parallel to the vertical medial plane of the locomotive and tender, the screw section in said intermediate conduit section lying in said aforesaid horizontal plane and being offset laterally from the screw section in said rearward conduit section.

4. In a locomotive and tender, a stoker comprising a rearward conduit section on the tender, a forward conduit section on the locomotive and an intermediate conduit section, said intermediate conduit section being movably connected with said forward conduit section in end-to-end relation therewith and having its opposite end offset laterally from and movably associated with said rearward conduit section, a screw section in each of said conduit sections, the axes of the screw sections in said forward conduit section and said intermediate conduit section lying in the vertical medial plane of the locomotive and tender and the axis of the screw section in said rearward conduit section being offset laterally from and parallel with the vertical medial plane of the locomotive and tender, the screw section in said rearward conduit section being positioned in an approximately horizontal plane and the screw section in said intermediate conduit section lying in the aforesaid horizontal plane.

WASHINGTON T. CAPPS.
